UNITED STATES PATENT OFFICE.

HERBERT B. BROUGHAM, OF WHITE PLAINS, NEW YORK, ASSIGNOR OF ONE-HALF
TO WALLACE CLARK, OF NEW YORK, N. Y.

SOAP-FLAKING DEVICE.

Application filed March 9, 1925. Serial No. 14,222.

This invention relates to improvements in soap flaking devices and containers therefor.

Some of the objects of the invention are: 5 to adapt for household use, the principle of the plane-edge in producing soap flakes by hand; to enable the user in a single operation to produce from bar soap, a flaky soap and to pack the same automatically; to utilize the container part of the device as a 10 receptacle for the soap flakes during the process of forming the same; and to control the sifting of the flakes from the container when dispensing the contents therefrom.

With these and other objects in view, the invention resides in certain novel construction and combination and arrangement of parts, the essential features of which are 15 hereinafter fully described, are particularly pointed out in the appended claim, and are illustrated in the accompanying drawing, in which:—

Figure 1 is a perspective view of my invention showing in dotted lines the closure member in open position.

Figure 2 is a vertical sectional view on the line 2—2 of Figure 1.

Figure 3 is a horizontal sectional view on the line 3—3 of Figure 1.

Figure 4 is a detail vertical sectional view on the line 4—4 of Figure 1.

Referring more particularly to the drawing, the reference numeral 10 designates a 35 box like metallic container having at least one of its side walls 11 provided with grating or shredding elements 12. The grating elements are punched from the side wall 11 by slitting the wall horizontally and then 40 pressing the material outwardly to form a substantially cupped shaped element. The elements 12 may be of varying sizes, that is, either coarse or fine depending upon the size of the flakes to be formed. While I 45 have only shown one side wall provided with a grating surface, it will be readily understood that all side walls may be similarly formed with grating elements of various sizes whereby different size flakes may be 50 manufactured.

One of the side walls adjacent the wall 11 is formed with an opening 13, through which a closure member or panel 14 is adapted to pass. The top and bottom walls of the

receptacle are formed with grooves 15 to 55 provide a track over which the panel is adapted to slide in its movement for sealing the openings formed by the grating elements when it is desired to dispense the contents of the receptacle, and for establishing communication between the grating surface and the interior of the container. The panel 14 serves as a valve for establishing and disestablishing communication between the grating surface and the interior of the receptacle, and although I have shown a sliding member for this purpose, it will be readily appreciated that an outside lid or various other means might be provided for performing the same function. The panel 60 14 is formed with a manipulating portion 16 for permitting the same to be controlled by the fingers of the hand when actuating the panel.

From the description thus far, it will 75 be seen that when the panel 14 is moved to the position shown in dotted lines in Figure 1 of the drawing and a bar of soap is passed over the grating surface, the flakes cut therefrom by the grating members 80 will collect within the container. When the container has been sufficiently filled, the panel is moved to a closed position and the contents of the container are ready to be dispensed for use.

For dispensing the flakes, there is provided an opening 17 in the top wall of the receptacle adjacent one corner thereof, and which is normally closed by a lid, panel or the like closure member 18 and having a 90 manipulating knob 19 movable in a slot 20 in the top. The lid 18 is adjustable with respect to the walls of the opening to regulate the size of the discharge opening to control the flakes of the contents therefrom 95 when the receptacle has been inverted for dispensing purposes. While the lid is shown as slidable over the opening, I wish it to be understood that the same may be hinged without in any way departing from the 100 spirit of my invention.

From the foregoing description, it will be seen that I have constructed a device whereby a bar of soap may be chipped or shaved into flakes or shreds which are automatically deposited in a container for discharge therefrom upon the inverting and shaking of the same. Such an article may be found espe-

cially useful in the household for preparing the soap for use in the washing of clothing, dishes and the like.

What is claimed as new is:—

- 5 A device of the class described comprising a box like receptacle having a grating surface on one of the side walls thereof which communicates with the interior of the same whereby a substance passed over said grating surface will be received within said receptacle in a flake condition, a panel slidably
- 10

mounted in said receptacle behind said grating surface for sealing the same with respect to the interior of said receptacle after the substance has been grated, and an outlet provided in the top wall of said receptacle through which the contents of said receptacle are discharged upon the inverting of the same. 15

In testimony whereof I have affixed my signature.

HERBERT B. BROUGHAM.
